(57) **CLAIM**

I claim the ornamental design for device for storing and cleaning medical instruments, as shown and described in the drawings.

DESCRIPTION

FIG. 1 is a top perspective view of a device for storing and cleaning medical instruments showing my new design; FIG. 2 is a top perspective view of thereof, with a portion being rotated; and,

FIG. 3 is a partial enlarged side perspective view thereof. The broken line showing of the indicia “KARL STOZ Germany” is for illustrative purposes only and forms no part of the claimed design.

1 Claim, 3 Drawing Sheets

FIG. 1

FIG. 2

FIG. 3
